DESCRIPTION

U.S. PATENT DOCUMENTS

D633,995 S * 3/2011 Chiang D23/332
D765,231 S * 8/2016 Horsfield D23/343

FIG. 1 is a perspective view of my new fire pit with height-adjustable legs design;

FIG. 2 is a front view thereof, the rear view being identical thereto;

FIG. 3 is a side view thereof;

FIG. 4 is a top view thereof;

FIG. 5 is a bottom view thereof; and,

FIG. 6 is a partially exploded view thereof.

In the drawings, the broken lines depict environmental subject matter only that forms no part of the claimed design.
